United States Patent [19]

Sugano et al.

[11] Patent Number: Des. 311,528

[45] Date of Patent: ** Oct. 23, 1990

[54] ELECTRONIC COMPUTER

[75] Inventors: Yoshihiko Sugano; Masahiko Tabuchi, both of Tokyo, Japan

[73] Assignee: Kabushiki Kaisha Toshiba,
Kanagawa, Japan

[**] Term: 14 Years

[21] Appl. No.: 80,683

[22] Filed: Aug. 3, 1987

[30] Foreign Application Priority Data

Feb. 13, 1987 [JP] Japan 62-5029

[52] U.S. Cl. D14/106

CLAIM

The ornamental design for an electronic computer as shown and described.

DESCRIPTION

FIG. 1 is a top, front, right side perspective view of an Electronic Computer showing our new design, the floppy disk being shown in broken lines for illustrative purposes only;

FIG. 2 is a front elevational view thereof;
 FIG. 3 is a right side elevational view thereof;
 FIG. 4 is a front elevational view thereof, the display panel in the closed position;
 FIG. 5 is a rear elevational view thereof;
 FIG. 6 is a right side elevational view thereof;
 FIG. 7 is a left side elevational view thereof;
 FIG. 8 is a top plan view thereof; and
 FIG. 9 is a bottom plan view thereof.

FIG. 1
